UNITED STATES PATENT OFFICE.

SVEN JULIUS STRID, OF CHICAGO, ILLINOIS, ASSIGNOR TO FRED MATHEWS, OF CHICAGO, ILLINOIS.

HOLDER OR SUPPORT FOR BRAKE GEARS.

Application filed August 5, 1925. Serial No. 48,430.

To all whom it may concern:

Be it known that I, SVEN JULIUS STRID, a citizen of the United States, and a resident of Chicago, Cook County, Illinois, have 5 invented certain new and useful Improvements in a Holder or Support for Brake Gears, of which the following is a full, clear, and exact description, such as will enable others to make and use the same.

10 My present invention relates to a holder or support for brake gearings for railway cars and has more particular reference to a device that is so constructed that the take up chain may be prevented accidentally 15 slipping off the winding drum and thus rendering the gear useless.

The means for holding or supporting the gears as a unit consists of top and bottom 20 castings that are connected together with the gears between them, and the bottom casting is provided with an extension or arm on 25 which the winding drum or windlass is rotatably mounted and there are horns or lateral extensions projecting from each side 30 of the arm alongside the drum which are so located that the take-up chain will ride thereon when slackened and will thereby 35 be prevented from slipping off the drum.

I prefer to carry out my invention and 40 accomplish the divers objects thereof in substantially the manner hereinafter fully described and as more particularly pointed out in the appended claims, reference being herein made to the accompanying drawings 45 that form a part of this specification.

In the drawings:—

Figure 1 is a longitudinal side elevation 50 of a break gear unit showing an embodiment of my invention.

Figure 2 is a top plan of the bottom member of the structure detached from the other parts of the unit.

Figure 3 is a vertical end elevation of the member shown in Fig. 2 and illustrating 55 the disposition of the horns.

The drawings, which illustrate a typical or preferred embodiment of my invention, are in a sense merely schematic for the purpose of illustration, and in said drawings 60 similar reference characters have been employed to designate like parts wherever the same appear throughout the several views.

The top member of the structure illustrated in Fig. 1 of the drawings is adapted 65 for attachment to the end-sill of the rail-

way car and consists of a horizontal disposed plate 5 that has its ends provided with depending flanges 6, and intermediate one of its longitudinal edges this plate is provided with a tapered extension 7, so that when the member is connected to the under portion of the end-sill the plate and its extension will project upon opposite sides of the sill. The plate and its extensions are provided with bearing bosses 8 to receive 65 the adjacent ends of the respective shafts or spindles upon which the gear elements are mounted.

The bottom member of the unit illustrated in Fig. 1 of the drawings is preferably an 70 integral casting and the details thereof are disclosed in Figs 2 and 3, wherein it will be seen the same consists of an elongated plate 9 that is somewhat widened transversely adjacent its ends 10 and has an up-standing flange 11 at each end edge. The plates 5 and 9 are preferably positioned 75 opposite each other in spaced planes with the respective flanges 6 and 11 overlapping and riveted to each other whereby the two 80 members are securely maintained in assembly as will be seen in Figure 1. The plate 9, mediate its ends, is provided with a bracket arm 12 formed integrally therewith and extended therefrom to provide a bearing boss 85 13 in vertical alinement with the boss in the extension 7 of the top member. This bracket arm 12 is disposed in a horizontal plane below and parallel with the plane of the plate 9 and it is connected with the lat- 90 ter by an oblique web or throat 14. A winding drum or windlass 15, having a lateral rim flange 16 and chain anchor 17, is interposed between the hub of the adjacent gear element and the bracket arm so 95 that, when the gear is operated to apply or release the brake, the chain is wound or unwound either on or off the drum. After the tension or power has been released the chain will become slack between the anchor 100 17 and its opposite end, and therefore is liable to become dismantled from the drum to an extent that will render the gear inoperative when it is attempted to apply 105 the brakes. To prevent this contingency 105 arising I have provided lateral horns 18 that extend outwardly and transversely to the bracket arm, and the outer portions of the horns are curved in an upward direction as shown in Figure 3 of the drawings 110.

so that should the chain accidentally become dislodged from the rim flange 16 of the drum this inclined portion will cause the chain to gravitate back to its normal or 5 desired position.

What I claim as new is:—

1. A device of the kind described comprising a top member, and a bottom member connected therewith, said bottom member 10 provided with a bracket arm, and horns projecting laterally from the outer portion of said bracket arm.
2. A device of the kind described comprising a top member, and a bottom member 15 connected therewith, said bottom member provided with a bracket arm that is off-set in a different plane from said arm, and horns projecting laterally from the outer portion of said bracket arm.
3. A device of the kind described comprising a top member, and a bottom member connected therewith, said bottom member consisting of an elongated plate, a bracket 20 arm extending from one of the longitudinal edges of said plate, and transversely disposed horns projecting from said arm, said horns being in substantial longitudinal alignment with each other and parallel with said plate.
4. A device of the kind described comprising a top member, and a bottom member connected therewith, said bottom member consisting of an elongated plate, a bracket 25

arm extending from one of the longitudinal edges of said plate and disposed in a plane 35 below the plane of said plate and connected therewith by an inclined web, and horns projecting from opposite sides of said bracket arm and having upwardly curved end portions.

5. In a device for mounting a brake-gear a member consisting of a horizontally disposed elongated plate, an oblique web projecting from one of the longitudinal edges of said plate, a bracket arm extending from 40 said web in a plane below and parallel with the plane of said plate, and lateral horns projecting from opposite sides of the outer portion of said arm and shaped concave upon their upper portions.

6. In a brake gearing consisting of two interengaged gear elements, and a winding drum connected with one of said elements, of a mounting therefor comprising top and bottom spaced plates rigidly connected together, each of said plates provided with lateral extensions intermediate their longitudinal edges, one of said extensions being off-set with respect to its plate where to accommodate said drum, and lateral horns projecting from said off-set extension upon opposite sides of said drum.

Signed at Chicago, in the county of Cook, and State of Illinois, this 7th day of July, 1925.

SVEN JULIUS STRID.
